FIG. I.

Fig. 3.

Fig. 2.

Meyer H. Finkelstein, Inventor
By his Attorneys
Frederick Neal

UNITED STATES PATENT OFFICE.

MEYER N. FINKELSTEIN, OF GREENWICH, CONNECTICUT.

LAMP.

1,273,473.

Specification of Letters Patent. Patented July 23, 1918.

Application filed October 11, 1917. Serial No. 195,913.

To all whom it may concern:

Be it known that I, MEYER N. FINKELSTEIN, a citizen of the United States, residing at Greenwich, Connecticut, have invented certain new and useful Improvements in Lamps, of which the following is a clear, full, and exact description.

This invention relates to improvements in lamps, such as head-lights for automobiles or the like, of the type in which the direct rays of light from the lamp are shielded at the upper portion of the front of the lamp so that the useful rays of light for the one driving the car are directed upon the ground in front of the lamp. One of the objects of the present invention is to provide means for illuminating, to a certain extent at least, the front surface of the light shield so that the front of said shield will not appear so darkly contrasted with the space through which the direct rays of light from the source of light are cast. Further objects of the invention are to provide a practical efficient and durable lamp of the type mentioned.

These being among the objects of the present invention, the same consists of certain features of construction and combinations of parts to be hereinafter described and then claimed with reference to the accompanying drawings illustrating an embodiment of the invention, in which—

Figure 1 is a front elevation of the improved lamp without the lens;

Fig. 2 is a central vertical section of the lamp; and

Fig. 3 is a horizontal section on the line 3—3 Fig. 1.

Referring to the drawings, the lamp casting 10 contains a main reflector 11 in which is located the source of light, here shown as an incandescent electric lamp 12, which is suitably mounted in the lamp in any well-known manner. Mounted upon the lamp is the lens 13, and preferably the improvements constituting the present invention are arranged within the lamp back of said lens.

Light intercepting means is provided by a semicircular shield 14 of sheet metal, the curved edge of which is provided with integral lugs 15 passed through slits in the mouth of the reflector 11 and turned over

and soldered to the back of said reflector, so that said shield covers approximately one-half of the said mouth, while its lower edge 55 16 will be located at the approximate diameter of the lamp.

Supported by the lower edge of the shield 14 is a narrow horizontal metallic strip 17, which extends substantially parallel with 60 the lower edge of the shield, and is provided with bent-up bracket portions 18 at the ends, which are soldered or otherwise suitably secured to the back of the shield, the reflector being thereby located in front of the lower 65 portion of said shield. Preferably the shield 14 is inclined slightly rearwardly while the strip 17 is inclined from its lower edge away from said shield so as to be positioned at an acute angle thereto. The adjacent surfaces 70 19 and 20 of the shield and strip 17 are so made as to constitute reflecting surfaces, with the result that the rays of light from a source of light positioned properly to the rear of the said surfaces will be reflected 75 from the surface 20 backwardly upon the reflecting surface 19 from whence the rays are again reflected in a forward direction. This will result in illuminating the front 80 surface 19 of the shield to such extent that it will not be dark as would ordinarily be the case, but will have a light value more in harmony with the direct rays of light which are cast below the shield forwardly from the lamp.

If an incandescent electric lamp such as 12 is employed to provide the illumination, a recess 21 is formed in the lower portion of the shield 14 so as to receive the lamp 12. Shielding means are also provided upon the 90 reflecting strip 17, which means are located directly in front of the incandescent electric lamp 12, so that no direct forward rays of light from the lamp will be cast in front of the lamp proper. To this end, the strip 17 95 is provided at about its mid-length with a shield which is formed integrally therewith and comprises an upwardly extending portion 22 provided with an inner reflecting surface and a downwardly extending portion 23 which is slotted vertically at 24. The slot 24 provides a gap for receiving the projecting apex of the electric lamp, which acts as an additional support for the adjacent

portions of the reflecting strip. Preferably, the lower projecting portion or lip 23 is formed, as shown in Figure, for enabling the one who applies the incandescent lamp to the lamp proper to do so more conveniently, and the edges of the portion 23 are preferably stiffened by bending them back as shown at 25.

It is obvious that the invention is susceptible of modification, as parts may be omitted, added and substituted without departing from the scope of the invention as claimed.

What I claim as new is:—

1. A lamp comprising a casing, light intercepting means to one side of the front thereof permitting the light within the lamp to be emitted from the other side of said front, and a reflector directly in front of said intercepting means for reflecting the said emitted light from within the lamp rearwardly upon the front surface of said intercepting means.

2. A lamp comprising a casing, an opaque light intercepting shield to one side of the front thereof occupying approximately one-half the area of the said front so as to cut off direct light from the lamp and permitting the light within the lamp to be emitted from the other half of said front, and a reflector directly in front of said shield for reflecting the said emitted light from within the lamp rearwardly upon the front surface of said shield.

3. A lamp comprising a casing, a reflector at the back thereof, light intercepting means to one side of the front of said casing so as to cut off direct light from the lamp and permitting the reflected light from said reflector to be emitted from the other side of said front, and an additional reflector directly in front of said intercepting means for reflecting light from within the lamp rearwardly upon the front surface of said intercepting means.

4. A lamp comprising a casing, a lens, light intercepting means back of said lens, having a space between it and said lens and positioned to one side of the front of said casing so as to cut off direct light from the lamp and permitting the light within the lamp to be emitted from the other side thereof, and a reflector forward of said intercepting means and back of said lens, and positioned for reflecting the said emitted light from within the lamp into said space rearwardly upon the front surface of said intercepting means.

5. A lamp comprising a casing, a source of light, opaque light intercepting means positioned directly in front of said source of light and located to one side of the front of said casing permitting the light to be emitted from the other side thereof, and

reflector forward of said intercepting means 65 for reflecting light from within the lamp rearwardly upon the front surface of said intercepting means, and means assisted by said light intercepting means for intercept-
ing direct light forward from said source of 70 light.

6. A lamp comprising a casing, a light intercepting shield to one side of the front thereof occupying approximately one-half of the area of the said front permitting light to be emitted from the other side thereof, and a narrow reflecting strip bridging the open front of said casing at the approximate diameter thereof, and located in front of the edge of said shield and extending approximately parallel with said edge, whereby it is adapted to reflect light from within the lamp rearwardly upon the front surface of said shield. 75 80 85

7. A lamp comprising a casing, a source of light therein, light intercepting means located in the approximate plane of said source of light to one side of the front of said casing, permitting the light within the casing to be emitted from the other side of said front, and a narrow reflecting strip bridging the open front of said casing at the approximate diameter thereof and located in front of the edge of said shield and extending approximately parallel with said edge, whereby it is adapted to reflect light from within the lamp rearwardly upon the front surface of said shield, said reflecting strip being provided at about its mid-length with a shield located in advance of the source of light for preventing direct rays of light being cast forwardly from the lamp.

8. A lamp comprising a casing, an incandescent electric lamp, light intercepting means located in the approximate plane of said incandescent electric lamp to one side of the front of said casing, permitting the light within the casing to be emitted from the other side of said front, and a narrow reflecting strip bridging the open front of said casing at the approximate diameter thereof and located in front of the edge of said shield and extending approximately parallel with said edge, whereby it is adapted to reflect light from within the lamp rearwardly upon the front surface of said shield, said reflecting strip being provided at about its mid-length with a shield located in advance of the incandescent electric lamp for preventing direct rays of light being passed forwardly from the lamp, and said strip-supported shield being provided with a gap in which the apex of said lamp is positioned.

9. A lamp comprising a casing, a back reflector, a lens, a source of light between said reflector and lens, a light intercepting shield located back of said lens to one side of the front of said casing and occupying

- approximately one-half of the area of the said front, permitting the light reflected from said back reflector to be emitted from the other side of said front, and an auxiliary reflector between said lens and said shield and in advance of said source of light for reflecting light from within the lamp rearwardly upon the front surface of said shield. 5
10. A lamp comprising a casing, light intercepting means to one side of the front thereof permitting the light to be emitted from the other side of said front, and a narrow horizontal reflector forward of said intercepting means for reflecting light from 15 within the lamp rearwardly upon the front surface of said intercepting means.
11. A lamp comprising a casing, a light intercepting shield of metal at the upper side of the front thereof occupying approximately one-half the area of the said front, permitting the light within the lamp to be emitted from the other half of said front, said shield having a reflecting front surface, and a reflector within the lamp and direct, 20 in front of said shield, and inclined outwardly from its lower edge for reflecting the said emitted light from within the lamp rearwardly upon the front surface of said shield.
30. 12. A lamp comprising a casing, a reflector at the back thereof, light intercepting means at the upper side of the front of said casing permitting the reflected light from said reflector to be emitted from the other side of said front, said intercepting means having a reflecting front surface similar to the reflecting surface of aforesaid reflector, and an additional reflector directly in front 35 of said intercepting means, and inclined outwardly from its lower edge for reflecting the said emitted light from within the lamp rearwardly upon the front surface of said intercepting means.
13. A lamp comprising a casing, a lens, light intercepting means back of said lens, positioned to one side of the front of said casing permitting the light to be emitted from the other side thereof, and a reflector forward of said intercepting means and 40 back of said lens for reflecting light from within the lamp rearwardly upon the front surface of said intercepting means, said reflector having means for positioning an incandescent electric lamp.
55. 14. A lamp comprising a casing, a source of light, light intercepting means positioned directly in front of said source of light and located to one side of the front of said casing, permitting the light to be emitted 60 from the other side thereof, and a reflector forward of said intercepting means and said source of light and inclined from its lower part away from said intercepting means, for reflecting light from within the lamp rearwardly upon the front surface of 65 said intercepting means.
15. A lamp comprising a casing, a light intercepting shield to one side of the front thereof occupying approximately one-half of the area of the said front, permitting 70 light to be emitted from the other side thereof, and a narrow reflecting strip bridging the open front of said casing at the approximate diameter thereof, and located in front of the edge of said shield and extending approximately parallel with said edge, said reflecting strip being inclined from its lower edge away from said shield, whereby it is adapted to reflect light from within the lamp rearwardly upon the front 75 surface of said shield.
16. A lamp comprising a casing, a source of light therein, light intercepting means located in the approximate plane of said source of light to one side of the front of 80 said casing, permitting the light within the casing to be emitted from the other side of said front, and a narrow reflecting strip located in the open front of said casing at the approximate diameter thereof and located in front of the edge of said shield and extending approximately parallel with said edge, whereby it is adapted to reflect light 85 from within the lamp rearwardly upon the front surface of said shield, said reflecting strip being inclined from its lower edge away from said intercepting means and being provided at about its mid-length with a shield located in advance of the source of 90 light for preventing direct rays of light 95 being cast forwardly from the lamp.
17. A lamp comprising a casing, an incandescent electric lamp, light intercepting means located in the approximate plane of said incandescent electric lamp to one side of 100 the front of said casing, permitting the light within the casing to be emitted from the other side of said front, and a narrow reflecting strip bridging the open front of 105 said casing at the approximate diameter thereof and located in front of the edge of said shield and extending approximately parallel with said edge, whereby it is adapted to reflect light from within the lamp rearwardly upon the front surface of said shield, said reflecting strip being provided 110 at about its mid-length with a shield, extending both above and below said strip, and located in advance of the incandescent 115 electric lamp for preventing direct rays of light being cast forwardly from the lamp, and the lower portion of said strip-supported shield being provided with a gap in which the apex of said lamp is positioned.
18. A lamp comprising a casing, a back reflector, a lens an incandescent electric lamp between said reflector and lens, a metallic light intercepting shield having a re-

4
reflecting front surface, and located back of said lens to one side of the front of said casting and occupying approximately one-half of the area of the said front, permitting the light reflected from said back reflector to be emitted from the other side of said front, said shield having a recess at the center of the front of said casting for receiving said electric lamp, and an auxiliary

reflector between said lens and said shield 10 and in advance of said electric lamp for reflecting light from within the lamp proper rearwardly upon the front surface of said shield.

Signed at New York city, N. Y., this 15.
9th day of October, 1917.

MEYER N. FINKELSTEIN.
